UNITED STATES PATENT OFFICE.

HENRY J. OSTER, OF ETHAN, SOUTH DAKOTA.

NON-REFILLABLE BOTTLE.

1,150,297.

Specification of Letters Patent. Patented Aug. 17, 1915.

Application filed May 6, 1914. Serial No. 836,766.

To all whom it may concern:

Be it known that I, HENRY J. OSTER, a citizen of the United States, residing at Ethan, in the county of Davison and State of South Dakota, have invented certain new and useful Improvements in Non-Refillable Bottles, of which the following is a specification, reference being had to the accompanying drawings.

10 This invention relates to improvements in non-refillable bottles, and has for its primary object to provide a very simple and efficient device of this character which will effectually prevent fraudulent refilling of the bottle after the same has been emptied.

15 The invention has for another object to provide a device of the above character which is so constructed that the parts thereof may not be manipulated by the insertion 20 of a wire or other instrument into the bottle neck.

25 Another and more particular object of the invention resides in the provision of a flap valve, and means for removably mounting the same in the bottle neck, and a ball having peripheral threads adapted for engagement with a single thread on the wall of the bottle neck, said ball engaging the flap valve when the bottle is in an upright position 30 and holding the same closed, and movable between said valve and the thread on the bottle neck when the bottle is inverted whereby the liquid may be decanted.

With the above and other objects in view, 35 the invention consists in novel features of construction, combination, and arrangement of parts as will be hereinafter referred to and more particularly pointed out in the specification and claims.

40 For a full understanding of the invention, reference is to be had to the following description and accompanying drawings, in which—

Figure 1 is an enlarged vertical section 45 through the neck of a bottle showing my improved non-refilling device arranged therein; Fig. 2 is a similar view, the bottle being inverted; Fig. 3 is a section taken on the line 3—3 of Fig. 1; Fig. 4 is a section taken 50 on the line 4—4 of Fig. 2; Fig. 5 is a detail perspective view of the valve-carrying disk; and Fig. 6 is a detail elevation of the ball.

Referring in detail to the drawings 5 indicates the neck of a bottle, the open end 55 of which is adapted to be closed by a suitable cork 6 in the ordinary manner. Upon

the inner wall of the bottle neck intermediate its ends a single inwardly projecting thread 7 is formed, said thread being recessed or notched at diametrically opposite points as indicated at 8. Spaced annular ribs 9 and 10 are also formed on the wall of the bottle neck inwardly of the thread 7 in spaced relation thereto, said spaced ribs forming an annular groove 11. The rib 9 at diametrically opposite points is cut away or recessed as at 12 for a purpose which will be later pointed out. As shown at 13, the upper surface of the annular rib 9 is curved and merges into the wall of the bottle neck. 70

A disk 14 formed preferably of aluminum is provided upon its edge at opposite points with outwardly projecting lugs 15. This disk is formed with a central opening 16, one end of which is flared as at 17 to provide a seat for the flap valve 18 which is hinged or pivoted upon the disk at one side of the opening therein as indicated at 19.

The ball 20 formed preferably of glass is provided with a plurality of threads 21 upon its periphery which are adapted for engagement with the single thread 7 on the bottle neck. This ball is slightly less in diameter than the interior diameter of the neck 5. Said ball is preferably formed 85 with spaced openings 22 to receive the prongs or tines of a suitable implement whereby the ball may be turned and threaded inwardly to its operative position.

In assembling the several parts of the device after the bottle has been filled, the disk 14 carrying the flap valve 18, is first inserted into the neck of the bottle, the lugs 15 on the edge of said disk passing through the recesses 8 in the annular thread 7 on the bottle neck, and also through the recesses 12 in the annular rib 9 until said lugs rest upon the lower rib 10. The disk 14 is then turned so as to dispose the lugs 15 out of registry with the recesses 12, said lugs retaining the disk in position between the ribs. The ball 20 is now inserted and turned by engaging the tool in the openings 22. The threads 21 on the ball coöperating with the thread 7 on the bottle neck causes the ball to be moved inwardly. When the threads 21 become disengaged from the thread 7, the ball moves into the space between the thread on the bottle neck and the disk 14. This ball resting upon the upper surface of the rib 9 and the flap valve 18 holds said valve 90 in its closed position.

This valve is prefer- 100
105
110

ably provided with a peripheral packing ring of rubber, cork, or other suitable material so as to provide an air-tight closure and exclude air from the interior of the 5 bottle. The parts being assembled in the manner above described, when the bottle is inverted to decant its contents, the ball 20 moves out of contact with the valve 18 and lodges upon the annular thread 7 on the 10 bottle neck. The valve 18 is thus forced to its open position by the pressure of the liquid and said liquid passes through the opening 16 in the disk 14 and around the ball, the same finally finding an outlet 15 through the notches or recesses 8 in the thread 7. It will be obvious that by the provision of the ball 20 and the manner of inserting the same in the bottle neck, after 20 said ball is once placed in position, the same can not be removed. The device, however, permits of the ready outward flow of the liquid when the bottle is inverted. The large ball resting upon the valve 18, absolutely precludes the possibility of the insertion 25 of a wire or other instrument into the bottle neck whereby said valve may be lifted from its seat and the bottle refilled. Thus, the fraudulent refilling of the bottle after 30 the same has been emptied of its contents is rendered impossible. It will also be appreciated that my invention, owing to its extreme simplicity, may be produced at a small manufacturing cost, and is highly reliable and efficient in practical operation. 35 While I have above described the preferred form, construction, and arrangement of the several elements employed, it will be understood that the device is susceptible of considerable modification therein, and I 40 therefore reserve the privilege of resorting to all such legitimate changes as may be fairly embodied within the spirit and scope of the invention, as claimed.

What is claimed is:

45 1. The combination of a bottle having a neck, a flap valve mounted in the inner end of said bottle neck, the wall of the bottle

neck having a single interior thread formed thereon between said flap valve and its outer end, said thread being provided with 50 a plurality of notches or recesses therein, and a spherical member having a series of peripheral threads for engagement with the single thread on the bottle neck whereby 55 said member may be disposed within the bottle neck for movement between said thread and the flap valve, said member normally resting upon said valve and acting to hold the same in its closed position.

2. The combination of a bottle having a 60 neck, a disk mounted in said bottle neck provided with a central opening, a flap valve normally closing said opening, said bottle neck being provided upon its inner wall with an annular rib in spaced relation to said 65 disk, a ball of less diameter than the bottle neck and movable between said disk and said rib, said rib limiting the outward movement of the ball, and said ball normally resting upon the flap valve and holding the 70 same in its closed position.

3. The combination of a bottle, a disk arranged in the neck of the bottle provided with a central opening, a flap valve normally closing said opening, said bottle neck 75 being also formed with an inwardly projecting annular thread spaced from said disk and having a plurality of notches therein, and a ball of less diameter than the interior 80 diameter of the bottle neck centrally provided upon its periphery with a plurality of annular threads for engagement with the thread of the bottle neck whereby said ball may be positioned in the bottle neck for 85 movement between the thread on said neck and said disk, said ball normally resting upon the flap valve and holding the same in its closed position.

In testimony whereof I hereunto affix my signature in the presence of two witnesses. 90

HENRY J. OSTER.
